UNITED STATES PATENT OFFICE.

GUSTAV M. OSTERBERG, OF HARRINGTON PARK, NEW JERSEY.

RAIL OILER.

Application filed March 24, 1924. Serial No. 701,308.

This invention relates to rail oilers and particularly to devices of this class designed for use in connection with elevators for lubricating the guide rails therefor; and the object of the invention is to provide a device of the class described composed of a box-shaped container having an integral projection at one side thereof, means being provided for mounting a wick or other fibrous body in connection with the projecting end portion of the container and further to the provision of means for supplying oil, placed in the container, to the wick or other fibrous body and thus to the rail to be lubricated; a further object being to provide a gravity feed oiler device of the class described and with means for controlling and regulating the feed of oil therefrom; a further object being to provide means for mounting the oiler in connection with the structure of an elevator and to properly position the projecting portion of the container thereof with reference to the guide rail or rails; and with these and other objects in view, the invention consists in a device of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a diagrammatic view showing the top corner portion of an elevator and a guide rail therefor, showing my improved oiler mounted in position.

Fig. 2 is a section detail view of the oiler shown in Fig. 1 and on an enlarged scale.

Fig. 3 is a view similar to Fig. 2 but showing only part of the construction and showing a modification; and,

Fig. 4 is a partial section on the line 4—4 of Fig. 3.

In Fig. 1 of the drawing I have shown at 5 one top corner portion of an elevator, at 6 one of the guide rails thereof, and at 7 one of the guide shoes of the elevator. This construction is old and forms no direct part of my invention, the same being shown solely for the purpose of illustrating one use thereof.

In carrying my invention into effect, I provide a box-shaped casing 8 which is ap-

proximately square in form and open at the top and at 9, I have shown a cover for closing the casing 8, said cover being hinged to the casing as shown at 10 and a spring 11 is mounted on the hinge of the cover and cooperates with the cover and the casing for normally holding the cover in a closed position. The bottom of the casing is provided at one side with a projecting member 12 apertured to receive a bolt 13. In mounting the casing in position, an L-shaped bracket 14 is employed, one end of the bracket being mounted in connection with the guide shoe 7 as shown at 15, while the casing 8 is adjustably mounted on the other end portion thereof and retained in position by the bolt 13. The other side of the casing 8 is provided with a projecting member 16, the outer end portion 17 of which is U-shaped in form and as shown in Figs. 1 and 2 of the drawing, is slightly enlarged or elongated. The U-shaped formation 17 of the member 16 forms a channel 18 in which the rail 7 operates. In the construction shown in Figs. 1 and 2 of the drawing, the member 16 is provided with an aperture 19 which opens into the casing and into the channel 18, and in practice a wick 20 is mounted in the casing and passed out through the aperture 19 and flared in the channel 18 of the member 16. A screw 21 is mounted in the member 16 and is adapted to extend into the aperture 19 to compress the wick 20 to control the feed of oil through said wick.

In the use of the device as shown in Figs. 1 and 2 of the drawing, it will be understood that the casing 8 is filled or partially filled with oil as indicated at 22 in Fig. 2 of the drawing and this oil feeds by gravity through the wick 20 and onto the rail 7. It will be noted that the aperture 19 is positioned above the bottom of the casing 8 and with this construction, when the level of oil drops below the aperture 19, the lubricant will siphon through the wick 20. Another advantage of this construction resides in the fact that any foreign elements in the oil or that may collect in the casing 8, will settle to the bottom thereof and may be cleaned out from time to time. It will also be understood that the adjustment of the screw 21 by reason of its compressing the strands of the wick 20 which normally are gaged to properly fit in the aperture 19, will control a feed of the oil to the rail 7.

and this feed may be increased or decreased at will.

In the construction shown in Figs. 3 and 4 of the drawing, the U-shaped extension 17 is of less vertical dimensions than in the construction shown in Figs. 1 and 2 of the drawing forming a shorter channel 18, and with this construction the member 16 is recessed at the bottom as shown at 23 to receive a comparatively heavy sheet of leather or similar material 24 which is recessed as shown at 25 to receive the rail 7, and the sheet 24 which constitutes the wiper element is retained in position by a sheet metal plate 27 fashioned to conform with the general shape of the sheet 24 and provided with upstanding side flanges 27 which overlap the sides of the member 16 or the U-shaped portions 17 thereof, the plate 26 being held in position by screws 28 passed through the flanges 27 and into the member 16.

I also preferably add a number of layers of leather or similar material 29 to the upper face of the sheet 24 at the outer or free ends thereof to form within the U-shaped portion 17 of the member 16 and upon the top of the sheet 24 around the rail, when the device is in use, a chamber 30 in which oil may be contained.

In the construction shown in Figs. 3 and 4, the aperture 19 is made smaller than the aperture 19 shown in Fig. 2 of the drawing and the screw 21 is made larger or is of a diameter sufficient to close the aperture 19 when the screw is seated on a seat 31 as clearly shown in Fig. 3 of the drawing. With this construction, a comparatively heavy oil is placed in the casing 8 and the feed of this oil into the chamber 30 is regulated by the screw 21, and it will be understood that no wick is employed. When the device is first put in use, it is preferred that the screw be adjusted to allow for a complete flushing of the rails or to provide a film of oil thereon, after which the screw may be adjusted to provide the proper feed of oil to keep the rails properly lubricated. In practice, it has been found that the use of my oiler, which will contain one pint of oil, will supply proper lubrication to the rail or rails of an elevator for a period of approximately one month after the rails have been covered with a film of oil. In the construction shown in Figs. 1 and 2 of the drawing, a light oil is preferably used rather than a heavy oil as in the construction shown in Figs. 3 and 4 of the drawing.

It will be understood that in the operation of the oiler as shown in Figs. 3 and 4 of the drawing, the leather or fibre sheet 24 together with the layers 29 will absorb a predetermined amount of the lubricant and will bear on the rail or on the edge and side faces thereof and provide for the proper lubrication. Whenever desired the fibre

sheet 24 and layers of fibre 29 may be replaced by simply removing the screws 28 and the sheet metal plate employed for retaining the fibre members in position. The layers 29 of fibre are preferably held in position by a screw rivet or the like 32, but it will be understood that these parts may be made of unitary construction if desired.

It will be understood that while I have shown certain details of construction for carrying my invention into effect, that I am not necessarily limited in these respects and various changes in and modifications of the construction herein shown and described may be made within the scope of the appended claims without departing from the spirit of my invention or sacrificing its advantages.

Having fully described my invention, what I claim as new and desire to secure by Letters Patent, is:

1. A lubricating device of the class described comprising a casing, a member projecting from the lower end portion of the casing, said member being of channel formation at its outer end, a fibrous body detachably mounted in connection with said member and fashioned to conform with the contour of the body to be lubricated, said member having an aperture opening into the lower end portion of the casing whereby the lubricant in the casing will feed by gravity outwardly through said aperture and into the channel above the fibrous body therein and adjustable means traversing the aperture in said member for controlling and regulating the flow of lubricant from the casing into said channel.

2. A lubricating device of the class described comprising a casing, a member projecting from the lower end portion of the casing, said member being of channel formation at its outer end, a fibrous body detachably mounted in connection with said member and fashioned to conform with the contour of the body to be lubricated, said member having an aperture opening into the lower end portion of the casing whereby the lubricant in the casing will feed by gravity outwardly through said aperture and into the channel above the fibrous body therein, adjustable means traversing the aperture in said member for controlling and regulating the flow of lubricant from the casing into said channel, and said adjustable means comprising a needle valve of greater diameter than the diameter of said aperture whereby the flow of lubricant from the casing through said aperture may be stopped in one position of said needle valve.

3. A lubricating device of the class described comprising a casing, a member projecting from the lower end portion of the casing, said member being of channel formation at its outer end, a fibrous body detach-

ably mounted in connection with said member and fashioned to conform with the contour of the body to be lubricated, said member having an aperture opening into the 5 lower end portion of the casing whereby the lubricant in the casing will feed by gravity outwardly through said aperture and into the channel above the fibrous body therein, the channel above the fibrous body comprising adjustable means traversing the aperture 10 in said member for controlling and regulating the flow of lubricant from the casing into said channel, said adjustable means comprising a needle valve of greater diameter than the diameter of said aperture whereby the flow of lubricant from the 15 casing through said aperture may be stopped in one position of said needle valve, and said fibrous body having raised walls extending into the channel of said member to form a supplemental storage chamber for 20 the lubricant within the channel of said member.

In testimony that I claim the foregoing as my invention I have signed my name this 20th day of March, 1924.

GUSTAV M. OSTERBERG.
